UNITED STATES PATENT OFFICE.

ANTON ROEMISCH, OF MORGANTOWN, WEST VIRGINIA, ASSIGNOR TO THE
SENECA GLASS COMPANY, OF SAME PLACE.

APPARATUS FOR GLAZING AND FINISHING ARTICLES OF GLASSWARE.

SPECIFICATION forming part of Letters Patent No. 664,058, dated December 18, 1900.

Application filed April 23, 1900. Serial No. 13,987. (No model.)

To all whom it may concern:

Be it known that I, ANTON ROEMISCH, a citizen of the United States, residing at Morgantown, in the county of Monongalia and State 5 of West Virginia, have invented new and useful Improvements in Apparatus for Glazing and Finishing Articles of Glassware, of which the following is a specification.

My invention relates to fire polishing and 10 finishing of articles of glassware, the same being particularly designed for use in connection with tumblers, goblets, and the like for the purpose of glazing and finishing off the rough or uneven edges of the same. It is not, 15 however, limited to this use.

The object of the invention is to provide an improved apparatus in which the feed of the same is under the control of the operator, in which a preliminary heating may be given 20 to the articles under treatment prior to their entrance into the main heating-chamber or furnace, and in which the glasses may be elevated and rapidly rotated by means independent of the carrier itself.

Other objects of the invention will herein-after appear, and what I regard as new will 25 be set forth in the claims.

In the drawings forming part of this specification, Figure 1 is a side elevation of an apparatus constructed in accordance with my 30 invention. Fig. 2 is a plan view of the same with the furnace, preliminary heater, and the supply-pipes connected therewith removed. Fig. 3 is a front elevation of the apparatus. Fig. 4 is a vertical central sectional view of the main heating-chamber or furnace. Fig. 35 5 is a detail plan view of the clamp for securing the parts thereof in place, and Fig. 6 is a detail sectional view of a modified construction of sprocket-chain constituting the glass-carrier.

Like reference-numerals indicate like parts in the different views.

The frame of the apparatus is made up of 45 the uprights 1 2 at the front of the machine and the uprights 3 4 at the rear thereof. The uprights 1 and 3 and 2 and 4 are connected by rails 5 6, both constructed, preferably, of angle-iron, with a vertical flange 7 and a horizontal or base flange 8. The vertical flange 7

of each rail terminates a short distance from the uprights at the ends of the machine, and the horizontal flange or base 8 of each rail is formed at its ends with integral lugs or projections 9, by means of which said rails are 55 secured to said uprights. The uprights 1 and 2 at the front of the machine are extended upwardly above the rails 5 and 6, are curved forwardly, and are connected at their upper ends by a cross-bar 10. Just beneath the 60 rails 5 and 6 said uprights 1 and 2 are connected by a cross-bar 11, formed with recesses 12 therein, and on this cross-bar said rails are supported at one end. The rear uprights 3 and 4 are connected at their upper ends by 65 a cross-bar 13, upon which the rails 5 and 6 are also supported. Mounted centrally of the cross-bar 11 upon a shaft 14 and located above said cross-bar is a sprocket-wheel 15, and mounted centrally of the cross-bar 13 and 70 upon the upper side thereof is a sprocket-wheel 16, both of the sprocket-wheels 15 and 16 being of the same size. Around the sprocket-wheels 15 and 16 passes a flexible carrier 17, the same being in the form of a 75 sprocket-chain which meshes with the teeth of said sprocket-wheels. A progressive movement is imparted to the carrier 17 by the rotation of the sprocket-wheel 15, and to effect this rotation the shaft 14, on which said 80 sprocket-wheel is mounted, has secured to it a ratchet-wheel 18, with which co-operates a pawl 19 on the operating-lever 20, mounted loosely on the lower end of the shaft 14. It will be observed that by moving the lever 20 85 backward and forward an intermittent rotation of the shaft 14, carrying the sprocket-wheel 15, may be effected, which action will cause a progressive step-by-step movement to be imparted to the carrier 17. 90

The carrier 17 is made up of the links 21 22, the cylindrical antifriction-rollers 23, and the bushing 24, extending through said links 21 and 22 and said rollers 23 and constituting the pivotal connection between the several 95 links of the carrier. The links 21 of each section of the chain are located outside the links 22 of the adjacent section, and said links are kept spaced apart by the rollers 23, which fit between the links 22. The bushing 24, which 100

serves as the pivot for the adjacent sections of the carrier, is formed with flanges or heads at its opposite ends, which serve to prevent the outward movement, and consequently the separation, of the links 21 and 22. It is also formed with a central longitudinal aperture 25, through which passes the stem 26 of a glass-holder 27. The upper end of the holder 27 is cup-shaped, as shown at 28, and is adapted to receive and retain in place a tumbler 29 or other article of glassware which is to be subjected to treatment in the apparatus. The lower end of the stem 26 of the glass-holder 27 is tapering, as shown at 30, and adjacent to said tapering portion 30 is a shoulder or abutment 31. It will be observed that the stem 26 of the holder 27 fits loosely in the aperture 25 of the bushing 24 and that the same is capable of vertical movement in the aperture 25 independent of the carrier.

Secured to the cross-bar 10, which connects the uprights 1 and 2 at the front of the machine, are two adjustably-mounted supports 32 for the main heater 33, the said supports being provided with elongated slots 34, through which the bolts or screws 35 pass for the purpose of securing the same to the cross-bar 10. The furnace 33 is made up of a base portion 36, a top 37, both constructed of fire-clay or other suitable refractory material, a protecting-cover 38, of metal, and a clamp 39 for retaining the parts in place. The base 36 is provided with a central opening 40, through which the tumblers 29 may be introduced, and with an annular groove or channel 41 surrounding the opening 40. It is also provided with an aperture 42, communicating with the channel 41, for a purpose which will presently appear. The clamp 39, as above stated, is provided for the purpose of retaining the parts of the furnace or heater 33 in place and for the attachment of the same to the supports 32. The same consists of two semicircular sections 43 44, pivoted together at their ends, as shown at 45, and provided with a thumb-screw or other securing means 46 at the opposite ends of said sections for the purpose of securing the same together. The ends of the sections 43 and 44 are extended outwardly, as shown, and provided with screw-threaded openings 47 48. The section 43 is also provided with a nozzle 49, which extends into the aperture 42 in the base portion 36 of said furnace. The lower ends of the supports 32 lie against the projecting ends of the sections 43 and 44 of the clamp 39, and screws 50 extend through openings in said supports and into the threaded openings 47 and 48 for the purpose of securing the furnace 33 to said supports. Secured to the nozzle or nipple 49 is a pipe 51, having a valve 52 therein, which is controlled and operated by a valve-rod 53, having an operating-handle 54 upon its upper end. Communicating with this pipe 51 is an air-dome 55, to which a supply of air under pressure is admitted through the pipe 56, having a valve or cock 57 therein. Adjacent to

the point of connection of the air-dome 55 with the pipe 51 is a supply-pipe 58 for gas or vapor fuel, having a cock or cut-off 59 therein. 70

In connection with the main heater or furnace 33 I provide a preliminary heater 60 for the purpose of moderately heating the tumblers 29 on the carrier 17 before they are subjected to the high heat of the furnace 33 to prevent the danger of breaking or cracking the same. The said preliminary heater 60 consists of an elongated hood having an inner lining 61, of fire-clay or other suitable refractory material, and provided with discharge-openings 62 in the upper side thereof. Communicating with the hood 60 at a point between the discharge-openings 62 is a branch pipe 63, which leads off from the gas-supply pipe 58 and is provided with a controlling-valve 64 therein. The means provided by me for elevating and rotating the glass-holders 27 separately and independently of the carrier 17 consists of a shaft 65, mounted in suitable bearings in a bracket 66 and in a hollow standard 67 and having a continuous rotary movement imparted thereto from a suitable source of power through the pulley 68 thereon. The upper end of the shaft 65 is provided with a tapering socket 69, adapted to receive the tapering lower end 30 of the stem of the glass-holder 27, and the lower end thereof is acted upon by a lever 70, fulcrumed upon a bracket or support 71 and connected through a link 72 with a foot-lever 73. The standard 67 is slotted, as shown at 74, for the passage of the lever 70, and a coil-spring 75 within the hollow standard 67 acts upon the shaft 65 to normally urge the same downwardly in opposition to the pressure exerted by the lever 70. 95

From the foregoing description it is thought that the operation of my device will be readily understood. Briefly stated, however, it is as follows: Two operators are required—one at the rear or feed end of the machine and the other at the front end of the machine—to operate the levers 20 and 73. Glasses are placed successively in the sockets 28 of the glass-holders 27 and are removed therefrom at the same end of the machine by the same operator. The operator at the front of the machine moves the lever 20 back and forth to impart an intermittent movement to the carrier 17, and the glass-holders 27, containing the tumblers to be treated, are successively brought to a point directly beneath the opening 40 in the base 36 of the furnace 33. As soon as a glass reaches this position the free end of the foot-lever 73 is depressed, which action, through the link 72 and lever 70, elevates the shaft 65 and brings the socket 69 on the upper end of said shaft into engagement with the tapering lower end 30 of the stem of the glass-holder 27. The said glass-holder is thereby elevated, bringing the upper edge or rim of the glass into the furnace 33 and simultaneously imparting to said glass-holder and the tumbler carried thereby 110 115 120 125 130 135

rapid rotary movement. The tumbler is caused to remain within the furnace 33 long enough to melt the edges thereof and to glaze and finish the same. As the flame in the furnace 33 is caused to traverse the groove or channel 41 therein, all parts of the edge of the glass will be subjected to the same heat applied to just the point at which it is required. When a sufficient time has elapsed to glaze and finish the glass, the pressure upon the foot-lever 73 is released and the shaft 65 and the glass-holder 27 at the upper end thereof are caused to return to their normal positions through the action of gravity and the spring 75 which surrounds the shaft 65. Said spring 75 also serves to disconnect the upper end of the shaft 65 from the lower end of the stem 26. Before reaching the heater 33, however, the glasses are subjected to a preliminary heating by being caused to pass beneath the hood 60, which constitutes the preliminary heater. This hood is supplied with gas or vapor fuel through the pipe 58 and the branch 63 thereof, and the products of combustion pass off through the discharge-openings 62. By this preliminary heating the danger of cracking or breaking the tumblers in the main heater or furnace 33 is overcome or at least reduced to a minimum. When the tumbler has been removed from the heater 33, the lever 20 is again operated to cause a further movement of the carrier 17 to bring the next glass-holder 27, containing a tumbler 29, beneath the heater 33, when the operation just described is repeated. It should be stated in this connection that by means of the air-dome 55, which receives air under compression from the air-supply pipe 56, and the gas-supply pipe 58, which enters the pipe 51 adjacent to the point of entrance of the supply of air from the dome 55, a complete and thorough mixture of air and gas is effected prior to the admission of the same to the furnace 33 and that the mixture is forced into the furnace by the blast furnished by the compressed air. The proportions of the mixture may be controlled by the valves 57 and 59 and the supply of the mixture to the furnace may be controlled by the valve 52. It should also be stated that the rails 5 and 6, which extend longitudinally of the machine and connect the uprights at the ends thereof, serve to support and guide the flexible carrier 17 and prevent the sagging thereof. It will be observed that the bases 8 of these rails do not extend far enough inwardly to interfere with the passage of the stems 26 of the glass-holders 27, but that the outer edges only of the lower links 21 of the carrier 17 bear upon the bases of these rails. The recesses 12 in the cross-bar 11 provide for the passage of the lower projecting ends of the stems 26 through said cross-bar.

It will be noted, further, that by the arrangement of the parts of my apparatus in which the horizontal carrier is employed, one part of which is caused to pass beneath the

melting-furnace 33, the tumblers or other articles to be subjected to treatment are fed upon the carrier at one end of the machine, are caused to pass beneath the preliminary heater 70 before entering the main heater or furnace, and are afterward caused to pass through the whole length of the machine before they are removed, thus giving time for the glasses to become thoroughly cooled before they are actually taken out of the apparatus. This is a feature of considerable importance.

In Fig. 6 of the drawings I have shown a modified form of glass-carrier in which the parallel separated links 21 and 22 and bushing 24, connecting the same, are dispensed with and instead single links 76 77 are employed. Each of the links 76 is formed at its opposite ends with an extension 78, having an opening 79 therein, the plane of the upper surface of each of the extensions 78 being below the plane of the upper surface of the body of the link 76. The opposite ends of the links 77 are formed with downwardly-extending hollow studs or projections 80, 90 which when the carrier is in its assembled position extend down through the openings 79 in the adjacent links. The stems 26 of the glass-holders 27 extend through the studs 80 and are vertically movable therein. The antifriction-rollers 23 surround the studs 80 and are held in place thereon by means of nuts or collars 81. When the parts are in place, the links 77 fit within the offset portion formed by the extensions 78, and the upper surfaces of the links 76 and 77 are practically in line with each other, as shown. The action of this form of carrier is identical with that heretofore described.

Having now described my invention, what I claim as new, and desire to secure by Letters Patent, is—

1. In an apparatus for glazing and finishing articles of glassware, the combination with a heater, of a horizontally-arranged, endless chain constituting a glass-carrier, and vertically-movable glass-holders extending through the pivots connecting the links of said chain.

2. In an apparatus for glazing and finishing articles of glassware, the combination with a heater, of a horizontally-arranged, endless chain constituting a glass-carrier, guides or supports therefor, and vertically-movable glass-holders extending through the pivots connecting the links of said chain.

3. In an apparatus for glazing and finishing articles of glassware, the combination with a heater, of a glass-carrier, glass-holders on said carrier, and means operating independent of the movement of said carrier for moving said holders longitudinally.

4. In an apparatus for glazing and finishing articles of glassware, the combination with a heater, of a glass-carrier, glass-holders on said carrier, a shaft for moving said holders longitudinally, means for coupling

said shaft separately to said holders, and means operating independently of the movement of said carrier for actuating said shaft.

5. In an apparatus for glazing and finishing articles of glassware, the combination with a heater, of a flexible, horizontally-arranged glass-carrier, glass-holders on said carrier, and a foot-lever for moving said holders vertically independent of said carrier.

10. 6. In an apparatus for glazing and finishing articles of glassware, the combination with a heater, of a glass-carrier, a plurality of glass-holders on said carrier, a rotating shaft, and means for coupling said shaft with each of said holders for rotating them.

7. In an apparatus for glazing and finishing articles of glassware, the combination with a heater, of a glass-carrier, glass-holders on said carrier, and means operating independently of the movement of said carrier for imparting a longitudinal movement to said holders and for rotating the same.

8. In an apparatus for glazing and finishing articles of glassware, the combination with a heater, of a glass-carrier movable beneath said heater, glass-holders on said carrier, means for imparting an intermittent progressive movement to said carrier, and means operating independently of the movement of said carrier for elevating and rotating said holders.

9. In an apparatus for glazing and finishing articles of glassware, the combination with a heater in which the glazing and finishing are effected, of means independent of said heater for imparting a preliminary heating to the articles under treatment prior to their entrance to said heater.

10. In an apparatus for glazing and finishing articles of glassware, the combination with a main heater, of a glass-carrier for conveying the articles to be treated to said heater, and a preliminary heater adjacent to said carrier but independent of and in advance of said main heater.

11. In an apparatus for glazing and finishing articles of glassware, the combination with a main heater, of a glass-carrier for conveying the articles to be treated to said heater, and an auxiliary heater independent of and in advance of said main heater, consisting of an elongated hood through which the glasses on said carrier are caused to pass on their way to the main heater.

12. In an apparatus for glazing and finishing articles of glassware, the combination with a heater, of a glass-carrier in the form of an endless sprocket-chain, horizontally-arranged sprocket-wheels on which said carrier is mounted, a ratchet-wheel secured to one of said sprocket-wheels, an operating-lever for said carrier having a pawl thereon adapted to engage said ratchet-wheel, glass-holders on said carrier, a longitudinally-movable rotary shaft, and means for coupling said shaft with said holders for moving the

same longitudinally and rotating them independent of said carrier.

13. In an apparatus for glazing and finishing articles of glassware, the combination with a heater, and means for adjusting the same, of a flexible horizontally-disposed glass-carrier movable beneath said heater, glass-holders on said carrier, and means independent of the movement of said carrier for moving said glass-holders vertically.

14. In an apparatus for glazing and finishing articles of glassware, the combination with a main heater, of an endless glass-carrier movable beneath the same, glass-holders on said carrier, means independent of the movement of said carrier for moving said glass-holders vertically, and a preliminary heater in the form of a hood independent of and located in advance of said main heater and adapted to embrace the glasses to be treated and heat the same before they reach said main heater.

15. In an apparatus for glazing and finishing articles of glassware, the combination with a glass-carrier, glass-holders thereon and means for moving said glass-holders longitudinally independent of said carrier, of a heater having an opening therein for the admission of the article to be treated and a groove or channel surrounding said opening, and means for supplying gaseous fuel to one point of said channel.

16. In an apparatus for glazing and finishing articles of glassware, the combination with a glass-carrier, glass-holders thereon, and means for moving said holders longitudinally independent of said carrier, of a heater consisting of a base having an opening therein for the admission of the article to be treated, having an annular channel around said opening and having an orifice therein leading into said channel, an imperforate top, and a clamp upon which said heater is supported, consisting of two pivotally-connected semicircular sections one of which is provided with a nipple which fits within said orifice, and means for securing the free ends of said sections together.

17. In an apparatus for glazing and finishing articles of glassware, the combination with a heater, of a clamping-band embracing the same, comprising two pivoted sections, the ends of which are provided with screw-threaded openings, supports for said heater fitting against the projecting ends of said sections, and screws extending through said supports into said screw-threaded openings.

18. In an apparatus for glazing and finishing articles of glassware, the combination with a heater having an opening therein for the introduction of the article to be treated, of a pipe communicating with the interior of said heater, an air-dome for compressed air connected with said pipe, and a gas-supply pipe also connected with said pipe, and valves for controlling the separate supply of air and

gas to said pipe and for controlling the supply of the mixture of air and gas to said heater.

19. In an apparatus for glazing and finishing articles of glassware, the combination with a heater, of a glass-carrier consisting of a chain made up of a plurality of links, anti-friction-rollers between the side links of said chain, and a hollow bushing for the reception of the stem of a glass-holder extending through each of said rollers and the links between which it is located.

20. In an apparatus for glazing and finishing articles of glassware, the combination with a heater, of a glass-carrier, a plurality of longitudinally-movable glass-holders on said carrier, a rotary shaft adapted to separately engage each of said holders, and means for moving said shaft longitudinally and for coupling said shaft with said holders for imparting a similar movement to said holders and for rotating the same.

21. In an apparatus for glazing and finishing articles of glassware, the combination with a heater, of a glass-carrier, longitudinally-movable glass-holders on said carrier, each having a tapering outer end, a rotary shaft having a socket therein adapted to receive

the tapering end of each of said holders, and means for moving said shaft longitudinally to impart a similar movement to said holders and to rotate the same.

22. In an apparatus for glazing and finishing articles of glassware, the combination with a heater, of a horizontally-disposed glass-carrier movable beneath the same, glass-holders on said carrier, vertically movable independently thereon, having their stems extending through said carrier and provided with tapering lower ends, a vertically-movable rotary shaft having a tapering socket in its upper end, a spring for maintaining said shaft in its lowered position, and a foot-lever for elevating the same to bring the tapering lower end of each of said holders into engagement with the socket in the upper end thereof for elevating said holders and imparting a rotary movement thereto.

In testimony whereof I have hereunto set my hand in presence of two subscribing witnesses.

ANTON ROEMISCH.
